UNITED STATES PATENT OFFICE.

ALEXANDER F. JENKINS, OF BALTIMORE, MARYLAND, ASSIGNOR TO THE ALEXANDER MILBURN COMPANY, OF BALTIMORE, MARYLAND, A CORPORATION OF MARYLAND.

ACETYLENE-GENERATOR.

1,081,503.

Specification of Letters Patent. Patented Dec. 16, 1913.

Application filed April 16, 1912. Serial No. 691,141.

To all whom it may concern:

Be it known that I, ALEXANDER F. JENKINS, a subject of the King of Great Britain, residing at Baltimore city, State of Maryland, have invented certain new and useful Improvements in Acetylene-Generators, of which the following is a specification.

This invention relates to acetylene generators and has reference more particularly to venting means for taking care of the gas that arises during the period of after-generation.

The invention is particularly an improvement adapted for use in connection with that type of generator shown in United States Letters Patent No. 956,358, granted to me April 26, 1910, and the purpose of the improvement is to adapt such a generator for use in indoor installations where the gas escaping during the period of after-generation would be dangerous on account of possibility of explosion and on account of its being inimical to life. With the type of generator disclosed in the said patent, gas is liable to generate for a short interval after the burner valve is closed and the gas rises freely through the water and escapes to the atmosphere. As the type of generator referred to is intended for out-of-door use, this escape of gas is not a particular disadvantage, but it would be where the generator is used inside a building. By means of the improvements hereinafter set forth, the gas that escapes during after-generation is allowed to blow off into a chamber which connects with a pipe that leads to a point outside the building where it can escape freely into the atmosphere without being dangerous.

For a more detailed understanding of the invention as regards its construction, operation and objects, reference is to be had to the following description, taken in connection with the accompanying drawings and to the claims appended hereto.

In the accompanying drawings, which illustrate certain embodiments of the invention, Figure 1 is a side elevation of the apparatus with the blow-off or venting chamber in section. Fig. 2 is a section on line 2--2, Fig. 1. Fig. 3 is a top plan view. Fig. 4 is a perspective view of a modified form of the improvement.

Referring to the drawings, A designates the tank of the generator which is provided under its bottom 1 with a washer B through

which the gas from the generator C passes so as to be cleaned before being supplied to the burners. The generator C is, to all intents and purposes, the same as that shown in the patent hereinbefore referred to so that the details thereof need not be shown or described, except to say that the water to act on the carbide enters the generator from the bottom and the gas resulting from the reaction of the water on the carbide passes to the washer through a conduit D which is composed of two telescoping sections 3 and 4, the telescoping portions being sealed by the water in the tank through which they extend. The gas from the conduit D enters the washer B from which it discharges through an outlet pipe E to the service pipe of the illuminating or other gas-consuming system. The structure thus far described is the subject-matter of the patent referred to, with the exception that the outlet pipe E, in the present instance, is located exterior to the tank A.

With a generator of this character, when not provided with a venting means, the gas during after-generation usually escapes at the lower end of the section 3 of the conduit D between the generator and washer, although it may also escape from the bottom of the generator with which there is a large after-generation, but the lower end of the pipe 3 is usually slightly above the bottom of the washer so that this being the point of least resistance, the gas will escape therefrom and bubble up through the water. To prevent the escape of the gas from the lower end of the pipe section 3 or from the bottom of the generator, provision must be made to allow the gas to escape from the outlet pipe under a head or pressure less than that existing at the points mentioned in the generating system within the tank, and for this purpose the improvements shown are provided. Preferably, although not necessarily, a chamber or compartment F is arranged outside the tank A that communicates therewith through an opening 5 so that in both the chamber and tank the water will be at the same level. From the upper end of the outlet pipe E, which terminates above the water level, extends a vent pipe 6 that leads downwardly through the chamber F and terminates at a point above the lower end of the pipe 3 within the tank. The pressure of the column of water above

the lower end of the pipe 6 is somewhat less than the pressure acting at the lower end of the pipe 3, and hence the gas during after-generation will pass from the generator through the conduit D, washer B, pipe E and vent pipe 6, and rise through the water in the chamber F. The top of the chamber F is closed by a cap or equivalent cover 7 which has an opening 8 into which 5 is threaded an escape pipe 9 that leads out of the building to the atmosphere. The pipe 6 communicates through an opening 10 and coupling 11 with the outlet pipe E. In this manner, the excess gas is free to pass 10 off to the atmosphere and will not escape into the building where the generator is 15 installed.

The gas from the chamber is supplied through a service pipe 12 to illuminating 20 burners, heaters, oxy-acetylene blow pipes and the like, the flow being controlled by a valve 12^a, and if desired, a pressure regulator 13 of any approved construction may be employed. In some instances, it may be 25 desirable to provide an automatic blow-off so that the pressure in the supply system may never exceed a certain amount, and hence a branch pipe 15 leads from the service pipe 12 back into the vent chamber F, 30 through an opening 16 in the cover 7. The outlet end of the branch pipe 15 is provided with a six-inch water seal 17, so that the gas will not escape by means of the vent chamber unless the pressure in the service 35 pipe exceeds that equivalent to a six-inch column of water. The seal 17 is automatically filled by water overflowing into it from the chamber F when the generator tank is filled to the required level.

40 In the modification shown in Fig. 4, the vent chamber F is in the form of a pipe instead of a sheet metal structure, as shown in Figs. 1 and 2, and as no blow-off device for the service pipe is employed, the chamber F need not be made so large. The gas 45 outlet pipe E' has a return branch 6^a which extends downwardly into the chamber F and is equivalent to the pipe 6 in Fig. 1 and operates in the same manner, the gas 50 escaping from the pipe 6^a being let off from the chamber F through the escape pipe 9^a. The outlet pipe F' has a valve 7 by which the flow of gas to the consumption system 55 can be cut off or opened.

55 From the foregoing description, taken in connection with the accompanying drawings, the advantages of the construction and of the method of operation will be readily apparent to those skilled in the art to which 60 the invention appertains; and while I have described the principle of operation of the invention, together with the apparatus which I now consider to be the best embodiment thereof, I desire to have it understood that 65 the apparatus shown is merely illustrative,

and that such changes may be made when desired as are within the scope of the claims appended hereto.

Having thus described the invention, what I claim as new, is:—

1. The combination of a water-containing tank, a gas generating means submerged and sealed therein and from which gas tends to escape during the period of after-generation, a chamber communicating with the tank whereby water in both is at the same level, an outlet pipe leading from the generating means, a vent pipe connected with the outlet pipe at a point above the water level and leading therefrom into the chamber and water-sealed therein at a pressure less than the water seal of the generating means, and an escape pipe for conveying away from the chamber the vented gas. 70 75 80

2. The combination of a tank, a generator therein, a conduit connected with the generator and composed of two telescoping sections sealed by the water in the tank, an outlet pipe receiving gas from the conduit, a vent pipe connected with the outlet pipe 85 and having a water seal of a less pressure than the water seal of the said conduit, and means for conveying away the gas escaping from the said vent pipe. 90

3. The combination of a tank, a generator submerged therein and from which gas during after-generation tends to escape at the bottom of the generator, a chamber communicating with the tank for holding water at the same level, an outlet pipe receiving gas from the generator, a pipe connected with the outlet pipe at a point above the water level and leading downwardly into the chamber with its lower end terminating above the bottom of the generator, and means for conveying away from the chamber the vented gas. 95 100 105

4. The combination of a tank, a generator submerged therein and from which gas during after-generation tends to escape at the bottom of the generator, a conduit connected with the generator and composed of two telescoping sections sealed by the water in the tank, an outlet pipe, a vent chamber containing a column of water, a pipe leading from the outlet pipe downwardly into the vent chamber and having its lower end terminating in the bottom portion of the said chamber, and means for conveying away from the said chamber the vented gas. 110 115 120

5. The combination of a tank, a generator submerged therein, a washer at the bottom of the tank, a conduit leading from the generator to the washer and composed of telescoping sections sealed by the water in the tank, an outlet pipe leading from the washer, a chamber communicating with the tank whereby both will contain water at the same level, a vent pipe leading downwardly into the chamber from the outlet pipe and 125 130

having its lower end terminating at such a point that the pressure of the water sealing the same is less than the pressure of the water sealing the telescoped sections of the said conduit, and means for conveying away the gas vented through the said vent pipe and chamber.

6. The combination of a tank, a generating means therein and from which gas tends to escape during the period of after-generation, a chamber communicating with the tank to receive water therefrom, an outlet pipe receiving gas from the said generating means, a vent pipe in constant open communication with and leading from the out-

let pipe into the said chamber and having its end sealed therein, a valve in the outlet pipe beyond the point of connection therewith of the vent pipe whereby gas can escape through the vent pipe when the said valve 20 is closed, a blow-off means connected with the outlet pipe at the discharge side of the said valve and leading into the said chamber, and a water seal for the blow-off pipe.

In testimony whereof I affix my signature in presence of two witnesses.

ALEXANDER F. JENKINS.
